GAME AND PRACTICING DEVICE

Stowell W. Mears, New York, N. Y.

Application August 3, 1940, Serial No. 350,815

3 Claims. (Cl. 273—29)

This invention relates to an improved game and practicing device.

It is a prime object of the invention to provide an improved game and practicing device which may be used in practicing and perfecting tennis strokes.

A further object of the invention is the provision of an improved device of the above character which by its inherent structure requires the player to use proper form in the execution of his strokes.

Among other objects is the provision of a game and practicing device of the above character which may be used indoors or outdoors, which does not require a great deal of space or special apparatus for its use, which may be used by one player alone and in addition to enabling the player to practice and perfect his tennis strokes also affords amusement and exercise.

Other objects of the invention will be apparent from the following detailed description.

In the drawing—

Fig. 1 is a perspective view of a game and exercising device embodying my invention, showing it in use;

Fig. 2 is an elevational view partly fragmentary of my game device;

Fig. 3 is a cross sectional view through the ball showing the manner in which the flexible resilient cords may be attached thereto;

Fig. 4 is a side view of the ball; and

Fig. 5 is a sectional view through the handle indicating the manner in which it may be attached to the flexible resilient cord.

In my improved game and practicing device I provide a ball 10 which is preferably, but not necessarily, a tennis ball, and I also provide suitable means for resiliently suspending the ball in the air at the proper distance from the player so that the player may hit or stroke the ball with a tennis racket and so that the player is required by the construction of the device to properly execute the strokes.

For this purpose I preferably support the ball by means of flexible resilient cords 11 and 12 made of rubber, rubber strands having a fabric covering, or some similar flexible resilient material as for instance metal springs. The flexible cords may be attached to the ball in any desired manner. However, in the case of a tennis ball I have found that the attaching means illustrated in the accompanying drawing is very satisfactory. This means comprises a flexible non-resilient tape 14 which is extended around the ball beneath the cover 15 and is formed into loops

16 which project outwardly through apertures in the cover formed at opposite sides of the ball. The cover 15 is a conventional tennis ball cover with the exception that the apertures are formed at opposite sides thereof. The flexible cords 11 and 12 are then extended through the loops 16 and knotted or otherwise secured in position. It will be seen that due to this construction the core of the ball is not pierced and the pressure in the ball is unaffected.

The length of flexible cord 11 may be varied and at its end it is preferably formed with a loop 17 which may be attached to a fixed support such as a hook on a wall or a door knob, as illustrated in Fig. 1. The end of flexible cord 12 is formed into a pair of diverging flexible resilient cords 18 and 19, cord 19 being an integral extension of cord 12 and the cord 18 being connected thereto by a slip knot 23 so that the relative lengths of portions 12 and 19 may be varied by adjusting the position of the knot.

The end of cord 18 is preferably attached to a handle such as the tubular wooden handle 20 and this may be accomplished by providing the handle with an aperture 21 at the center thereof through which the cord 18 is extended, a knot being formed at the end of the cord to prevent its removal. The handle 20 is adapted to be grasped in the hand of the player when the device is in use.

The end of cord 19 is preferably formed with means such as loop 22 adapted to be engaged by the foot of the player when the device is in use.

In using the device the loop 17 of flexible resilient cord 11 is attached to a fixed support as for instance a hook on a wall or a door knob as shown in Fig. 1. In practicing forehand strokes a right-handed player grasps the handle 20 in his left hand in a natural manner and places the loop 22 around his left foot, as also shown in Fig. 1. He then grasps the handle of the tennis racket in his right hand and a forehand stroke can be executed in the usual manner.

When the ball is struck by the racket it will rebound at first in the usual manner. However, the resilient cords will cause it to return to its original position. In practicing backhand strokes the device is assembled in the same manner with the exception that the loop 22 is placed around the right foot of the wearer. In the case of a left-handed player it will be appreciated that the handle 20 should be grasped in the right hand and in executing forehand and backhand strokes the loop 22 should be placed around the

opposite foot from that indicated in connection with a right-handed player.

As previously stated, the cord 11 may be varied in length so as to suit the general requirements of the place in which the device is used. The cords 12, 18 and 19 should be properly proportioned in length, however, so that the ball is suspended in the air a proper distance from the player so that he can execute a normal forehand and backhand stroke. This can be varied within limits to suit the requirements of individual players by adjusting the position of knot 23 and also by increasing or decreasing the tension on the elastic cords. The length of cord 18 should be such as to cause the player to bend forward slightly so that the full power of his weight can be put into the stroke and so as to keep his head down.

It will be seen that because of the manner in which the device is constructed and used it causes the player to stand properly with his shoulders substantially at right angles to the imaginary position of the net. Also, it causes him to hit the ball when it is in the proper position, i. e., in front of the player, more particularly in the case of a right-handed player, in front of his left foot on a forehand stroke and in front of his right foot on a backhand stroke. The device also tends to induce the player to use a full stroke with a full "follow through" in order to prevent his wrist, arm or racket from being struck by the cord on the rebound. At the same time it prevents the player from cutting the ball and causes him to use a full stroke either flat or with top spin.

If desired, a suitable target may also be supported near the ball and this may consist of a fabric target supported by flexible rubber strands, the object being for the player to cause the ball to hit a predetermined portion of the target. The target should be positioned slightly above the height of the net. The accuracy of the shot can be readily determined by the proximity of the ball to the target.

It should be understood that the device may be used in different manners than illustrated and described herein. Thus, for instance, instead of grasping the handle 20 the player may grasp the portion 19 or 12 of the cord enabling him to hold the cord high enough to practice chop or slice shots. Also, at times the end 17 of cord 11 may

be attached at a relatively high point so that the cords are disposed at a sharp angle. In the latter instance the handle 20 is not utilized and may be omitted entirely. In this manner of using the device, chop or slice shots may also be practiced and the left hand may be left free for balance. For practicing serving the loops 17 and 22 are attached to relatively high points as for instance across the corner of a tennis court back stop, so as to suspend the ball at the proper height for serving for the particular player.

It should also be understood of course that various modifications may be made in the illustrated and described embodiment of my invention without departing from the invention as set forth in the accompanying claims.

I claim:

1. A game and practicing device for use in practicing tennis strokes comprising a ball, and 20 a pair of resilient flexible cords connected to and extending from opposite sides of the ball, one of said cords being adapted to be connected to a fixed support and the other of said cords being formed at its end with a pair of diverging flexible resilient cords one of said last-mentioned cords being adapted to be grasped in the hand of the player and the other of said last-mentioned cords being adapted to be attached to a foot of the player whereby the ball is resiliently suspended in the air adjacent the player.

2. A game and practicing device for use in practicing tennis strokes comprising a ball and 30 a pair of flexible resilient cords connected to and extending from opposite sides of the ball, one of 35 said cords being adapted to be attached adjacent its end to a fixed support and the other of said cords being formed with two diverging flexible resilient cords one of said last-mentioned cords being provided with a handle at the end thereof adapted to be grasped in the hand of the player and the other of said last-mentioned cords being formed with means at the end thereof adapted to engage a foot of the player whereby the ball is resiliently suspended in the air adjacent the player.

3. A game and practicing device as set forth in claim 2 in which one of the last-mentioned cords is attached to the other last-mentioned cords by a slip connection whereby their relative lengths may be varied.

STOWELL W. MEARS.
